[57] CLAIM

The ornamental design for a terminal outlet box for an electrical track for room lighting system, as shown and described.

DESCRIPTION

FIG. 1 is a bottom plan view of a terminal outlet box for an electrical track for room lighting system showing our new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof and,

FIG. 7 is a bottom perspective view thereof.

The phantom line showings of FIGS. 1-6 shows the environment in which our new design is used.
